UNITED STATES PATENT OFFICE.

JACOB HENDRICKSON, OF NORTHPOR, WASHINGTON.

PERMUTATION-PADLOCK.

1,101,075.

Specification of Letters Patent. Patented June 23, 1914.

Application filed February 4, 1914. Serial No. 816,602.

To all whom it may concern:

Be it known that I, JACOB HENDRICKSON, a citizen of the United States, residing at Northport, in the county of Stevens and State of Washington, have invented a new and useful Permutation-Padlock, of which the following is a specification.

The present invention appertains to a permutation padlock, and aims to provide a novel and improved device of that character.

It is the object of the present invention to provide a permutation or combination padlock, embodying a shackle and manually controllable tumblers within the padlock case, for normally maintaining the shackle in closed position, and for permitting the shackle to be slid when the tumblers are set properly.

A further object of the present invention is to provide a padlock of the nature indicated, wherein means are provided whereby changes in the combinations of the tumblers may be effected in a simple and convenient manner.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention has been illustrated in its preferred embodiment in the accompanying drawing, wherein:—

Figure 1 is a side elevation of the improved padlock, in open condition. Fig. 2 is a sectional view of the padlock in closed condition, the section being taken along the median plane of the device. Fig. 3 is a central longitudinal section of the lock. Fig. 4 is a sectional detail taken on the line 4—4 of Fig. 2.

In carrying out the present invention, there is provided a suitable padlock case 1, which has its sides or faces, bottom and top split or divided, to provide the two sections 2 and 3, which have their bottom or lower end portions hinged together, as at 4, whereby the sections of the case may be swung open and closed. The lower end or bottom portion of the section 3 preferably projects beyond the side or back portions,

as seen in Fig. 1, whereby the face or side portions of the section 2 may overlap the said projecting lower end or bottom portion when the sections are closed or folded together. 60

The face or side portions of the section 2 are preferably larger or greater in extent, than those of the section 3, the sides or faces of the case being divided at one side of the center of the case to that end. Spindles or arbors 5 are journaled through the face or side portions of the section 2, centrally of the case, and have knurled heads or knobs 6 at their outer or remote ends for permitting the spindles or arbors to be readily rotated by hand. 65

Secured to the inner ends of the spindles or arbors 5, is a pair of tumbler disks 7, which have the inner bosses or hubs 8 keyed or otherwise engaged upon the inner ends of the spindles, it being preferable to provide the bosses or hubs 8 with square or non-circular openings engaging over the squared or non-circular inner ends of the spindles 70

5. The tumbler disks 7 are provided with the inturned or inwardly projecting marginal or peripheral flanges 9 which have their edges spaced slightly apart, each of the flanges or lips 9 being provided with a chordal notch or slot 10 for the purposes 80 which will hereinafter appear. 85

A dial disk 11 is mounted rotatably upon each of the spindles or arbors 5, between the corresponding tumbler disk 7 and face or side of the case, the dial disks being slightly larger in diameter than the tumbler disks, so that their peripheral portions project beyond the tumbler disks. The outer or remote sides of the dial disks are provided 95 with graduations or indicia along the margins or peripheries of the said disks, and the face or side portions of the section 2 of the case are provided with openings or slots 12 adjoining the upper end or top of the 100 case, through which the graduations or indicia are visible from the outside, for enabling the tumbler disks to be set properly, as will hereinafter more fully appear.

In order to adjustably connect the dial 105 disks 11 to the tumbler disks 7, each of the dial disks is provided with an annular series of apertures 13, which are confined within the faces or sides of the case, when the case is closed, a screw or key 14 being passed 110 through one of the apertures 13 of each dial disk and taking into the threaded aperture

15 provided in the corresponding tumbler disk. It is evident, at this point, that each of the dial disks is made fast to the corresponding tumbler disk, by the clamping screw or key 14, whereby the dial disks will be rotated with the tumbler disks, when the shafts or spindles 5 are rotated. It will also be evident that by withdrawing the screws or keys 14, the dial and tumbler disks 16 may be rotated or swung with respect to one another, in order to change the combinations as will hereinafter appear, the screws or keys 14 being passed through the proper apertures 13 so as to again engage the apertures 15 of the tumbler disks.

The free end or top portions of the sections 2 and 3 of the case, are provided with interengaging or interfitting lugs or projections 16 whereby, when the sections are closed, they will be locked against springing or shifting laterally relative to each other, which would be objectionable.

A latch or catch 17 is pivoted upon the free end or top of the section 2, adjoining one face or side portion thereof, and is adapted to swing over the upper end or top of the section 3, when the two sections are swung together, to thereby retain the case in closed condition, under ordinary conditions.

30 The shackle 18 of the padlock, is of U-shape, and has a reduced extension 19 at one end which is insertible into or through the socket or aperture 20 formed in the upper or free end of the section 2, the extension or finger 19 being relatively short, so as not to engage the tumbler disks when the extension 19 is inserted through the aperture 20. Projecting from the other end of the shackle 18, is a relatively long projection or shank 21 which passes through an aperture or bore 22 formed in the upper end or top of the section 3 of the case, and which has its sides flattened, as at 23, from a point spaced from the end of the shackle 18, to a point short of the free end of the shank 21, to provide the head or shoulders 24 at the free end of the said shank. The shank 21 is provided with a longitudinal slot 25, and a retaining pin 26 is engaged through one side of the section 3 adjoining its upper end, in order that the inner end of the pin 26 will engage the slot 25 so as to permit the shackle to slide inwardly and outwardly to a limited extent, but preventing the shackle from being removed, unless the pin 26 is withdrawn.

The projection or shank 21 is of such a length that the head or shouldered portion 24 is projectable through the slots or notches 10 of the tumbler disks, when the said slots or notches are swung in alinement with the aperture or bore 22, in order that the head or shouldered portion 24 may lock within the flanges 9 of the tumbler disks under certain conditions, that is, when the tumbler

disks are so swung, that the slots or notches 10 are out of alinement with the aperture or bore 22 to break up the combination.

In use, when the sections of the case are folded together, or closed, those portions of the dial and tumbler disks projecting from the section 2, as seen in Fig. 1, will be housed within the section 3, the graduated portions of the dials being exposed through the openings or slots 12 in the sides or faces 75 of the case. When the tumbler disks are swung to the proper positions, whereby the channels or slots 10 aline with the aperture or bore 22, this being readily accomplished by bringing the proper numerals or indications within the openings 12, will enable the shackle to be opened and closed. Thus, supposing the shackle to be opened or slid outwardly, the projection or finger 19 being disengaged from the aperture or socket 20, 85 and the projection or shank 21 being drawn outwardly out of engagement with the tumbler disks, to close or lock the shackle, it is merely necessary to slide or force the same inwardly so that the projection or 90 finger 19 enters the aperture or socket 20, and so that the free or headed end of the shank 21 passes through the slots or notches 10 of the tumbler disks, to bring the headed or shouldered portion 24 within the annular 95 lips or flanges 9. Then by disarranging the tumblers, by rotating the spindles or shafts 5, the flanges or lips 9 will engage over the head or shouldered portion 24 of the shank 21, and will thus lock the shackle in closed 100 position, the shoulders of the head or portion 24 engaging under the lips or flanges 9 to prevent the withdrawal of the shank 21 from the tumbler disks.

To open the lock, it is merely necessary to 105 rotate the tumbler disks to set position, the setting of the tumbler disks being readily accomplished by means of the dial disks 11, as above intimated, so that the channels or notches 10 will aline with the aperture or bore 22 to permit the withdrawal of the headed or shouldered end of the shank 21, from between the tumbler disks. Thus, the finger 19 may be withdrawn from the aperture or socket 20 to open the shackle, 115 whereby the shackle may be detached from or applied to a hasp keeper, or any other object, the present device being employed in the same capacities as an ordinary padlock.

The pin or key 26 engaging the slot 25 of the shank 21 will prevent the shackle from being rotated, and will also limit the outward movement of the shackle, in order that the same cannot be detached, although it may be slid to the necessary extent in opening and closing the shackle.

Ordinarily, when the case is closed, the latch 17 is engaged to the free end of the section 3 of the case, and will lock the sections in closed position. To change the com- 130

bination of the lock, the sections 2 and 3 are opened, by first opening the shackle 18 so that the extension 19 is released from the section 2, the latch 17 also being released 5 from the section 3, to permit the two sections to swing apart or unfold as suggested in Fig. 1. Then, by withdrawing the screws or keys 14, after the same have been exposed, as seen in Fig. 1, the dial disks may 10 be set to different positions or to the new positions desired, in which event, the screws or keys 14 may be passed through the apertures 13 alining with the apertures 15 of the tumbler disks, to engage the said apertures 15 for again securing the dial disks to the tumbler disks. This enables a large 15 number of combinations to be had, according to the number of indications upon the dial disks. After the dial disks have been 20 readjusted or reset with respect to the tumbler disks, the sections 2 and 3 may be closed, and the latch 17 then engaged to the free end of the section 3 to lock the sections together under ordinary conditions when it 25 is not desired to open the sections of the case.

From the foregoing, taken in connection with the drawing, the advantages and capabilities of the present device will be obvious 30 to those versed in the art, without further comment, it being noted that the objects aimed at have been carried out satisfactorily.

Having thus described the invention what is claimed as new is:—

35 1. A permutation padlock embodying a case comprising two sections hinged together at one end, a shackle carried by the free end of one section engageable with the free end of the other section, and locking means disposed within one section of the case and engageable with the shackle, the locking means being arranged to be exposed 40 when the sections of the case are swung apart.

45 2. A permutation padlock embodying a case comprising two hinged sections, a shackle having one end portion slidably engaging the free portion of one section of the case, the free portion of the other section of 50 the case having means for receiving the other end portion of the shackle, and locking means disposed within one section of the

case and engageable with the first mentioned end portion of the shackle.

3. A permutation lock comprising a case 55 embodying two separable sections, a shackle carried by one section of the case and engageable with the other, manually operable tumblers mounted within one section of the case for engaging the shackle, dials disposed 60 in coöperative relation with the tumblers, the case having openings to expose the dials, and adjustable means for attaching the dials to the tumblers and normally housed within the case. 65

4. A permutation padlock embodying a case comprising two hinged sections, a shackle having one end portion slidably carried by the free portion of one section of the case, the free portion of the other section of 70 the case having a socket to receive the other end portion of the shackle, tumblers mounted within one section of the case and engageable with the first mentioned end portion of the shackle, dials associated with the 75 tumblers, the case having openings to expose the dials, and adjustable means connecting the dials to the tumblers and normally housed within the case.

5. A permutation padlock embodying a 80 case comprising two hinged sections, a shackle having one end portion slidably carried by the free portion of one section of the case, the free portion of the other section of the case having a socket to receive the other 85 end portion of the shackle, spindles journaled through one section of the case, tumblers carried by the inner ends of the spindles, and engageable with the first mentioned end portion of the shackle, dials 90 mounted loosely upon the spindles between the tumblers and the adjacent portions of the case, the case having openings exposing the graduated portions of the dials, and adjustable means for attaching the dials to the 95 tumblers and normally housed within the case.

In testimony that I claim the foregoing as my own, I have hereto affixed my signature in the presence of two witnesses.

JACOB HENDRICKSON.
